UNITED STATES PATENT OFFICE.

JAMES D. HOUSTON, OF EAST AURORA, NEW YORK.

MECHANICALLY-WAVED FLAG.

1,374,921.

Specification of Letters Patent. Patented Apr. 19, 1921.

Application filed October 11, 1920. Serial No. 416,071.

To all whom it may concern:

Be it known that I, JAMES D. HOUSTON, a citizen of the United States, residing at East Aurora, in the county of Erie and State of New York, have invented certain new and useful Improvements in Mechanically-Waved Flags, of which the following is a specification.

This invention relates to display apparatus, and the primary object of the invention is to provide a non-fabric flag which can be mechanically operated in such a manner as to simulate the waving of a fabric flag in a breeze.

15 Another object of the invention is to provide a display device for either indoor or outdoor use, which will present a pleasing and novel appearance to the eye, and which includes a plurality of sections arranged to 20 simulate the appearance of an American flag, said sections being adapted to be operated in such a manner as to give the effect of a flag waving.

25 A further object of the invention is to provide an improved patriotic display device constructed to simulate the appearance of an American flag, which includes a plurality of vertically disposed rollers having a plurality of stripes painted or otherwise formed 30 thereon in an undulated formation, and means for simultaneously rotating said rollers in one direction, whereby the device will produce a wavy effect.

35 A still further object of the invention is to provide a novel display device of the above character which will be durable and efficient in operation, one that will be simple and easy to construct, and one which can be manufactured and set up at a reasonable cost.

40 With these and other objects in view, the invention consists in the novel construction, arrangement and formation of parts as will be hereinafter more specifically described, claimed and illustrated in the accompanying 45 drawings, forming a part of this specification, in which drawings:

Figure 1 is a side elevation of the improved patriotic display device.

Fig. 2 is a top plan view of the same 50 showing parts thereof in section.

Fig. 3 is a fragmentary front elevation of the improved display device showing the rollers turned one quarter of a revolution from that disclosed in Fig. 1, showing the 55 relation of the painted stripes on the rollers

in relation to each other whereby the wavy motion is presented.

Fig. 4 is a fragmentary side elevation of one of the rollers illustrating the manner in which the stripes are formed on the rollers 60 in relation to each other.

Fig. 5 is an enlarged fragmentary front elevation of a modified form of the display apparatus, parts of the same being shown in section and showing the novel means for 65 illuminating the interior of the rollers so as to form an illuminating display apparatus for night purposes.

Referring to the drawings in detail, wherein similar reference characters designate corresponding parts throughout the several views, the letter A indicates the improved display apparatus which includes a supporting frame B and the novel flag displaying device proper C.

The frame B is of substantially open rectangular configuration and includes the upper and lower longitudinally extending rails or beams 10, and the vertically disposed end or transverse beams 11. The upper and 80 lower longitudinally extending beams 10 are provided with a plurality of bearing openings which are arranged in vertical alinement for a purpose which will be hereinafter more specifically described.

85 The novel flag displaying apparatus proper C includes a plurality of rollers 12 and a plurality of rollers 13. These rollers 12 and 13 are arranged within the frame B in vertical longitudinal alinement and are 90 adapted to have painted or otherwise formed thereon the stripes and the stars and field therefor so as to present the appearance of the American flag. The manner in which the stripes are painted or otherwise formed 95 on the rollers will hereinafter be more specifically described, as the manner in which they are formed on the rollers presents the waving motion to the flag when the rollers are rotated, by a means which also will be 100 hereinafter more fully described.

The plurality of rollers 12 and the plurality of rollers 13 are formed substantially the same with the exception that the rollers 12 have painted or otherwise formed thereon 105 the blue field 14, the stars 15 and the white and red stripes 16 and 17, while the rollers 13 have only painted or otherwise formed thereon the red stripes 18 and the white stripes 19. As shown, each of the rollers 110

includes a cylindrical body which may be formed solid and out of wood or of hollowed formation and out of sheet metal, such as aluminum, tin or the like. The upper and 5 lower ends of the rollers are provided with spindles 20 which are rotatably mounted in the bearing openings formed in the upper and lower longitudinally extending bars 12. The red and white stripes painted or otherwise 10 formed on the rollers are of undulated formation and have the highest point thereof designated by the numeral 21 directly diametrically opposite the lowest point thereof as designated by the numeral 22. 15 Thus when these rollers are simultaneously rotated in the same direction, it can be seen that a wavy effect will be produced giving the appearance of a flag waving in a breeze. The rollers 12 have, as stated, painted or otherwise 20 formed thereon above the white and red stripes 16 and 17, the blue field 14 and the stars 15 and the upper edge of the blue field painted on each one of the rollers also terminates in an undulated manner. 25 If so desired, the terminals of the rollers may be cut off or trimmed in accordance with the shape of the upper and lower edges of the uppermost and lowermost stripes formed on the rollers, or if so desired, the 30 rollers may have their terminals above and below the stripes and the blue field painted a dull black or other suitable color as at 23 which will blend in with the surrounding atmosphere or interior decorations. Worm 35 wheels 24 are keyed or otherwise secured to the upper terminals of the upper spindles 20 of each of the rollers and these worm wheels are engaged by a horizontally disposed longitudinally extending worm 25 40 which may be rotated in any preferred manner, such as by an electric motor or the like. This longitudinally extending worm 25 is rotatably mounted in suitable bearing brackets 26 bolted or otherwise secured to the upper 45 surface of the uppermost longitudinally extending bar or beam 10.

In operation of the improved patriotic display device, all of the rollers are adapted to rotate simultaneously and in a counter-clockwise direction and as the rollers rotate the position of the stripes thereof will change in relation to each other thus presenting a wavy appearance simulating a flag waving from the left toward the right. 50 If the display apparatus is to be used at night, a suitable arc light can be trained on the same for the illumination thereof, or if so desired, the device may be constructed as illustrated in Fig. 5 of the drawings. 55

In Fig. 5 of the drawings, the rollers, which are designated by the numerals 27 in this form, are constructed of hollow cylindrical formation and of translucent material, such as glass, celluloid, or the like, and 60 these hollow cylinders are secured to upper

and lower plugs 28 and 29. The upper plugs 28 are provided with spindles 30 which are rotatably mounted in the uppermost longitudinally extending beam 10 of the frame B, and these spindles are provided with the 70 worm wheels 24 and are adapted to be rotated simultaneously by the worm 25. The lower plugs 29 are provided with hollow spindles 31 which are rotatably mounted in suitable openings formed in the lowermost 75 longitudinally extending bar or beam 10. The plug 29 is also formed hollow and has its upper face concaved as at 32 and this concaved face 32 is adapted to rotatably receive a suitable reflector 33, which is carried by a hollow sleeve 34, which is secured by suitable fastening elements 35 to the lowermost longitudinally extending beam 10. This sleeve 34 is adapted to receive a suitable plug 36 and suitable incandescent 80 bulb 37 and the plug 36 may be fed from any suitable source of electrical energy through electric wires 38. It thus can be seen that while the rollers 27 are being rotated, the incandescent lamp 37 mounted therein will 85 illuminate the interior thereof and the rays of light will shine through the translucent material from which the rollers are made. It is to be understood, of course, that the rollers are painted in the same manner as 90 the rollers 12 and 13 in the form shown in Figs. 1 to 4 inclusive.

From the foregoing description it can be seen that an improved patriotic display apparatus has been provided of exceptionally 100 simple and durable construction, which will present a pleasing and novel appearance to the eye and form a general attraction to the public.

Changes in details may be made without 105 departing from the spirit or scope of this invention; but,

I claim:

1. A display apparatus comprising a plurality of rotatable cylindrical rollers arranged side by side having a series of superposed obliquely disposed rings of different colors arranged thereon, and means for simultaneously rotating said rollers whereby a wavy motion will be presented. 110

2. An American flag display apparatus comprising a frame, a plurality of rollers rotatably mounted in said frame arranged side by side, certain of said rollers having a blue field and stars arranged thereon, and superposed red and white stripes formed thereon below the field, the other rollers having superposed red and white stripes, the stripes being arranged obliquely with their highest point directly diametrically opposite their lowest points, and means for rotating said rollers whereby a horizontal up and down waving motion will be presented. 120

3. An American flag display apparatus comprising a rectangular open frame in- 125

cluding longitudinal bars and transverse side bars, a plurality of rollers having spindles rotatably mounted in the longitudinally extending bars, said rollers having 5 superposed obliquely disposed stripes of different colors formed thereon, worm wheels keyed to the spindles at one end of the rollers, and a worm meshing with said worm wheels.

10 4. A display apparatus comprising a frame, a plurality of rotatable rollers carried by the frame having outwardly extending spindles formed on their terminals rotatably mounted in the frame, the rollers having arranged thereon a series of superposed obliquely disposed stripes of different colors, means for rotating said rollers, the spindles formed on one end of the rollers being of hollow formation, a sleeve secured to the 15 same for non-rotary movement arranged within the hollow spindles, electric plugs carried by said sleeves, and incandescent lamps fitted in said sleeves arranged to electrically engage said plugs and disposed 20 within said rollers.

25 5. A flag display apparatus comprising a frame, a plurality of cylindrical rollers formed of translucent material of hollow formation arranged within the same, spindles

carried by the terminals of the rollers and 30 mounted for rotary movement in the frame, the spindles carried by one end of the rollers being of hollow formation, sleeves disposed in said hollow spindles and non-rotatably secured to the frame, reflectors arranged within the transparent rollers and secured within said sleeves, electric plugs detachably fitted within said sleeves, and incandescent lamps detachably fitted within said sleeves and disposed within said translucent rollers. 35

6. In a display apparatus of the above character, a hollow cylindrical roller formed of translucent material, plugs carried by the opposite ends of the cylinder, outwardly extending spindles formed on the plugs, one of the plugs having its face concaved and its spindle of hollow formation, a non-rotatable sleeve mounted within said hollow spindle, a reflector fitted within the concaved portion 40 of the said concaved plug and secured to said sleeve, an incandescent lamp arranged within the translucent roller and detachably fitted within said sleeve, and a removable electric plug fitted in said sleeve arranged to 45 electrically engage said incandescent lamp. 50 55

JAMES D. HOUSTON.
